UNITED STATES PATENT OFFICE

JOHN H. WOODALL, OF WOODLAND, GEORGIA, ASSIGNOR TO GEORGIA CUSHION AND WRAPPER COMPANY, OF WOODLAND, GEORGIA, A CORPORATION OF GEORGIA

PAD FOR FRUIT CONTAINERS

Application filed March 10, 1928. Serial No. 260,620.

This invention relates to an improvement in the cushioning pad for fruit containers disclosed in my earlier Patent, No. 1,632,722, granted June 14, 1927. The present pad has the same general structure and purpose of the patented device, in that it comprises a bat of resilient fibrous material enclosed by a casing consisting of a facing formed of waterproof paper and a backing of tough paper, the margin of the backing being overlapped by folded marginal parts of the facing adhering thereto. As set forth in the specification of the patent, the purpose of the waterproof facing is to protect the fibrous bat from moisture and the tough paper backing reinforces the pad to withstand rough handling. The pad of the patent is shaped to adapt it to rectangular containers, while the present pad is of a structure particularly adapted to cylindrical containers, such as circular baskets and barrels.

In the harvesting and shipment of fruit there has come into general use a bushelling basket formed of staves shaped to form a cylindrical body part and a rounded bottom. To opposite sides of the basket, handles are attached that project above the rim of the basket and the lid is fitted between these handles. The lid is formed of a hoop having the same diameter as the rim of the basket and extending diametrically across the hoop and secured thereto are stave strips nailed together at their intersection. With the lid in place on the basket, the hoop of the former is seated on the rim of the latter. In packing these baskets, ordinarily a circular pad is used that fits the interior diameter of the basket so that it can be readily positioned on the fruit. While an exact fit of the pad is not required, yet its diameter should not exceed the space between the basket handles so that when the pad is positioned it will not be rumpled or distorted by being forced between the handles. In the circular pad in ordinary use, the material of the bat is scanty adjacent the edge of the bat. When the pad of a diameter to pass smoothly between the handles is positioned on the fruit, it has been found that the scanty edge part of the pad is in-

sufficient to protect the fruit adjacent to the rims of the basket and lid.

One of the objects of the present invention is to provide a cushioning pad particularly adapted to be used in circular containers and especially in bushelling baskets, the structure of the pad being such as to provide ample protection for the fruit packed adjacent to the rims of the basket and its lid. This is accomplished by forming the pad with a diametrical area slightly greater than the corresponding area at the mouth of the basket so that the edge of the positioned pad extends slightly outside of the basket rim. This extension of the pad projects the scanty edge part outside of the container so that a thick part of the pad overlies the fruit adjacent to the rims of the basket and lid to provide the required protection. To permit this extension of the pad, the latter on opposite sides is cut away so that it can be fitted between the handles without becoming rumpled or distorted. Often bushelling baskets are provided with four handles. To accommodate these handles, the pad is given an octagonal shape, which provides the opposite cut-away sides for baskets provided with two or four sides. This octagonal formation of the pad also facilitates the embodiment of certain structural features, hereinafter pointed out in detail, that are an advantage to the pad; also, the octagonal formation permits the employment of a novel method for the manufacture of the pad, whereby certain improvements in the product are attained.

In the shipment of fruit in containers, particularly in refrigerator cars, it is important that ventilation be provided to prevent deterioration. To facilitate this, the pad is provided with ventilating openings and in the pad of the present invention the edges of these openings are reinforced by strips that prevent tearing of the thin waterproof paper of the pad facing, these reinforcing strips extending through the pad and binding together the face and back tending to strengthen the pad and to prevent displacement of the fibrous material forming the resilient bat.

In the drawings, in which similar refer-

ence characters designate corresponding parts,

Figure 1 is plan view of the reverse side of the facing for the pad, showing the arrangement of the folds in the paper.

Figure 2 is plan view, showing the back of a completed pad, and

Figure 3 is an enlarged detail sectional view on the line 3-3 of Figure 2.

Referring more particularly to the drawings, the pad comprises the bat 10 of resilient fibrous material, such as excelsior, enclosed by a casing formed of a facing 11 of waterproof paper and a backing 12 of stout paper. The pad is octagonal in shape, having four long sides 13 of equal length interspersed with four short sides 14 also of equal length. With the pad in place in a container filled with fruit, the waterproof facing 11 contacts with the fruit and prevents moisture therefrom entering the material of the bat. The tough paper of the backing 12 reinforces the pad so that it will withstand rough handling.

The facing 11 is formed of a sheet of paper of rectangular shape having an area considerably greater than that of the completed pad. In the formation of the pad, preliminary to folding the facing sheet, the latter is positioned with its four corners in diagonal extension of the four short sides 14, corresponding to the four short sides of the completed pad. In the formation of the pad, these four corner parts of the facing sheet are folded over the short sides 14 in triangular folds 15 to overlap the back of the bat. Also, the intermediate parts of the facing sheet, between the corner parts, are folded over the long sides 13 in rhomboidal folds 16 to overlap the back of the bat. In forming the folds, beneath one side of the triangular fold a tuck is formed in the paper, as indicated by dotted lines at 17, and on the other side of the triangular fold, as at 18, a tuck is formed beneath the end of the adjacent rhomboidal fold 16.

By superimposing the larger triangular folds over the smaller rhomboidal folds, an even surface is prepared for the subsequently applied backing.

With the folds 15 and 16 in place against the back of the bat, the backing 12 of tough paper is pasted over the folds to close the casing. In outline the backing is the same as is that of the pad, but the backing is of less area so that a somewhat flexible margin is provided at the edge of the pad. At intervals the pad is provided with ventilating openings 19 extending through the same, preferably through the folds 15 of the facing. To form a ventilating opening, a square aperture is cut through the pad at about the central part of the fold 15. To protect the edges of the opening against accidental tearing and to prevent closing of the opening by the shift-

ing of the fibrous filling, binding strips 20 are pasted over the edges of the casing at the opening. These strips also serve to bind together the facing and backing to stiffen the pad as a whole.

In forming the pads in actual practice, the shaping and folding of the parts will not follow the exact geometrical outlay indicated in the drawings, but will follow the same more or less roughly according to the skill and care exercised by the operator.

What I claim is:

1. A cushioning pad for a cylindrical fruit container, comprising a fibrous bat shaped to approximately a circular contour to fit the rim at the mouth of the container; and a protective casing enclosing the bat consisting of a facing extending over the face of the bat and folded over the entire edge of the bat with the folds overlying the back of the bat; and a reinforcing backing extending over the back of the bat and pasted over the folds to close the casing, said backing being of less area than the bat to provide a flexible margin adjacent the edge of the bat covered only by the facing and the folds formed of the facing.

2. A cushioning pad for cylindrical fruit containers, comprising a fibrous bat of polygonal contour adapted to fit a cylindrical container; and a protective casing enclosing the bat consisting of a facing extending over the face of the bat and folded over the edge of the bat to form a series of folds overlying the back of the bat with a fold coincident with each of the sides of the polygonal contour; and a reinforcing backing extending over the back of the bat and pasted over the folds to close the casing.

3. A cushioning pad for cylindrical fruit containers, comprising a fibrous bat of polygonal contour adapted to fit a cylindrical container; and a protective casing enclosing the bat consisting of a facing extending over the face of the bat and folded over the edge of the bat to form a series of major folds interspersed with a series of minor folds, the folds of both series extending over the back of the bat and each fold being coincident with a side of the polygonal contour of the bat; and a reinforcing backing extending over the back of the bat and pasted over the folds of both series to close the casing.

4. A cushioning pad for cylindrical fruit containers, comprising a fibrous bat of polygonal contour adapted to fit a cylindrical container and having a series of comparatively long sides interspersed with a series of comparatively short sides; and a protective casing enclosing the bat consisting of a facing extending over the face of the bat and folded over the edge of the bat to form over the back of the bat a series of triangular folds coincident with the shorter sides of polygonal contour and also a series of rhomboidal folds coincident with the longer sides of the polyg-

onal contour; and a reinforcing backing extending over the back of the bat and pasted over the major and minor folds to close the casing.

5. A cushioning pad for fruit containers, comprising a fibrous bat and a protective casing therefor, said casing consisting of a facing extending over the face of the bat and folded over the edge of the bat to form over 10 the back a plurality of folds, and a reinforcing backing extending over the back of the bat and pasted over the folds thereon to close the casing, the casing and bat having ventilating openings extending through the same and 15 through the folds of the casing overlying the back of the bat, and binding strips folded over the edges of the openings.

6. A cushioning pad for cylindrical fruit containers, comprising a fibrous bat of octagonal contour adapted to fit a cylindrical container and a protective casing for the bat, said casing being formed of a square sheet of paper preliminarily positioned on the face of the bat with the corners of the sheet in 25 diagonal extension of opposite sides of the octagonal bat, the corners of the sheet being folded over said sides to form folds extending over the back of the bat, and a reinforcing backing extending over the back of the 30 bat and pasted over the folds thereon to close the casing.

7. A cushioning pad for cylindrical fruit containers, comprising a fibrous bat of octagonal contour adapted to fit a cylindrical container and protective casing for the bat, said casing being formed of a square sheet of paper of greater superficial area than that of the bat, the square sheet of paper being preliminarily positioned on the face of the 35 bat with the corners of the sheet in diagonal extension of opposite sides of the octagonal bat, said corners being subsequently folded over the adjacent sides of the bat to form a series of triangular folds extending over the 40 back of the bat and those parts of the sheet between the triangular folds being folded over the adjacent sides of the octagonal bat to form a series of rhomboidal folds extending 45 over the back of the bat in interspaced relation with the triangular folds, and a reinforcing backing extending over the back of the bat and pasted to the triangular and rhomboidal folds to close the casing.

In testimony whereof I hereunto affix my 50 signature.

JOHN H. WOODALL.
